LOWER RAIL FOR VENETIAN BLINDS

Harry S. Rosenbaum, Baltimore, Md.

Application November 25, 1940, Serial No. 367,113

5 Claims. (Cl. 156—17)

This invention relates to Venetian blinds and has particular reference to the construction of the bottom rail of such blinds.

It is an object of the present invention to provide a bottom rail formed entirely of metal so constructed as to avoid the possibility of warping or twisting, while at the same time being extremely light in weight and ornamental in appearance.

A further object of the invention resides in the construction of a bottom rail so formed as to permit the attachment of the conventional blind tapes and operating cords without the use of external means such as tacks or the like, such attaching means being easily and quickly performed without the aid of tools.

Another and important object of the invention is the provision of a bottom rail that is extremely simple in construction, is strong, durable, cheap to manufacture and is highly convenient in use.

Other and important objects of the invention will present themselves during the course of the following description, reference being had to the accompanying drawing, wherein—

Figure 1 is a fragmentary side elevation of the lower part of a Venetian blind showing the invention in use.

Figure 2 is an enlarged end elevation thereof.

Figure 3 is a fragmentary perspective view of one end of the bottom rail.

Figure 4 is a transverse section taken on line 4—4 of Figure 1 and.

Figure 5 is a fragmentary plan view of one end of the rail.

Referring specifically to the drawing, the numeral 5 designates a Venetian blind as a whole, having the usual slats 6. Supporting tapes 7 are employed for the slats as is customary. It should be noted here that the tapes as here employed have their lower ends formed in an integral loop instead of the usual separate attaching ends.

The numeral 8 indicates the lower rail as a whole, embodying an elongated channel body portion 9 having inclined sides 10. The sides 10 have their upper free edges formed into rolled portions 11. The channel body 9 is closed by ends 12. The channel 9 is adapted to be closed by a sliding cover 13 arched throughout its length and having its edges engaging beneath the rolled portions 11 of the sides 10.

Arranged inwardly of the ends of the rail 8 and formed in the side walls 10, are slots 14. The slots 14 are formed in the walls 10 in parallelism with the rolled edges 11. Arranged intermediately

10 of the ends of the slots 14 are vertically arranged slots 15, communicating with the slots 14 and passing entirely through the rolled edges 11. As clearly shown, the slots 14 and 15 are arranged in pairs diametrically opposite to each other in the side walls 10. As shown, when in use the slide 13 normally closes the slots 15. The slots 14 and 15 serve as a means for attaching the tapes 7.

15 The numeral 16 designates slots formed in the slide member 13, the number of such slots corresponding to the number of slots 14 and 15. The slots 16 terminate in enlarged circular openings 17 and 18, the opening 17 being relatively larger in diameter than the opening 18. The slots 16 and openings 17 and 18 serve as attaching means for the lift cords 19. The cords 19 are knotted at their lower attaching ends as at 20.

20 In use, when it is desired to assemble the blinds, the slats 6 are first mounted in the usual way on the supporting tapes 7 with the lift cord passing through all the slats and projecting for a substantial distance below the lowermost slat.

25 The cord is then knotted at its end as shown at 20. As before pointed out, the tapes are formed in a complete loop at their lower ends. The slide 13 is then moved outwardly of the channel a distance sufficient to uncover the slots 15. The

30 loops of the tapes are then inserted edgewise through the slots 15 and into the slots 14. The slide 13 is then moved into its normal position to cover the slots 15, thus providing a means for preventing accidental displacement of the tapes 35 from the slots 14. The knots 20 are then inserted through the large openings 17 and moved longitudinally of the slots 16 to lie beneath the smaller openings 18. The openings 18 are of such size as to prevent passage of the knots 40 therethrough.

45 It will be seen from the foregoing that an extremely simple means has been provided for mounting the lower rail of the blind. The method of assembly is such as will permit the attachment of the lower rail with a minimum of effort. Removal of the rail for any purpose is equally simple. No tools are required to assemble or disassemble the device. The rail is formed of light gauge metal and its design presents an ornamental and attractive appearance.

50 It is to be understood that the invention is not limited to the precise construction shown, but that it includes within its purview whatever changes fairly come within either the terms or the spirit of the appended claims.

Having described the invention, what is claimed is:

1. In a Venetian blind, the combination with a lower rail of channel formation, supporting tapes for the blind having their lower extremities formed in a continuous loop, lift cords for the blind having their lower ends knotted, slots formed in the channel for the reception of the loops, means carried by the channel for retaining the loops in the slots and means formed in the channel for attaching the knotted ends of the cords.

2. In a Venetian blind, the combination with a lower rail, supporting tapes for the blind having their lower extremities formed in a continuous loop, lift cords for the blind having their lower ends knotted, said lower rail being of channel formation having a removable top, slots formed in the channel for the reception of the tape loops, slots formed in the removable top for the reception of the knotted ends of the cords and means whereby said removable top serves to retain said tapes in the first named slots.

3. In combination a Venetian blind having supporting tapes and lift cords, of a lower rail for said blind, said rail being of channel formation having a removable top, said channel hav-

ing slots formed in its opposite side walls for the reception of said tapes, said top having slots formed therein for the reception of said cords, said top when in the closed position serving to retain the tapes in the first named slots.

4. A lower rail for Venetian blinds comprising an elongated channel member, a slideable top for closing said channel, T-shaped slots formed in said channel for the reception of tapes carried by the blind, said slideable top when in position serving to close said slots, slots formed in said top and terminating in enlarged opening, said last named slots adapted to receive the ends of lift cords carried by the blind.

5. A rail of the character described comprising an elongated channel member having closed ends and inclined sides, said sides having their upper edges rolled, a top member for the channel slideable under the rolled edges, said top member formed convex transversely, diametrically oppositely arranged transverse pairs of slots formed in the sides, vertical slots intersecting said slots and the rolled edges, said top provided with longitudinal slots, said last named slots terminating in enlarged circular openings, as and for the purposes specified.

HARRY S. ROSENBAUM.
